Primary Examiner — Rosemary K Tarcza*Assistant Examiner* — Nathaneil D Buckner(74) *Attorney, Agent, or Firm* — Barley Snyder(57) **CLAIM**

The ornamental design for a glass mount, as shown and described.

DESCRIPTION

FIG. 1 is a front, top and right side perspective view of a glass mount, showing the new design;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof;

FIG. 7 is a bottom plan view thereof; and,

FIG. 8 is another front, top and right side perspective view of the glass mount in FIG. 1.

The broken lines shown in the Figures are included to show unclaimed subject matter only and form no part of the claimed design.
